UNITED STATES PATENT OFFICE.

ROBERT MUIR, OF WATERTOWN, MASSACHUSETTS, ASSIGNOR TO HOOD RUBBER COMPANY, OF WATERTOWN, MASSACHUSETTS, A CORPORATION OF MASSACHUSETTS.

DESIGN FOR A SOLID TIRE.

Application filed October 25, 1923. Serial No. 7,589. Term of patent 3½ years.

To all whom it may concern:

Be it known that I, ROBERT MUIR, a citizen of the United States, and a resident of Watertown, in the county of Middlesex and State of Massachusetts, have invented a new, original, and ornamental Design for Solid Tires, of which the following is a specification, reference being had to the accompanying drawing, forming part thereof.

In this drawing:

Figure 1 is a plan view of a portion of a tire embodying this design, and

Fig. 2 is a transverse section on line 2—2 of Fig. 1.

Fig. 3 is a fragmentary perspective view.

I claim:

The ornamental design for a solid tire as shown.

ROBERT MUIR.
